(57) **CLAIM**

I claim the ornamental design for octagon weight, as shown and described.

DESCRIPTION

FIG. 1 is a front plan view of an octagon weight;

FIG. 2 is a rear plan view thereof;

FIG. 3 is a side elevational view of the octagon weight, all eight sides being a mirror image thereof;

FIG. 4 is a rear side isometric view thereof;

FIG. 5 is a front isometric view thereof;

FIG. 6 is a front isometric view thereof; and,

FIG. 7 is an isometric view of two octagon weights shown in a condition of use.

The broken lines in the drawings are for the purpose of illustrating portions of the article that form no part of the claim.
